ARC FURNACE CONTROL APPARATUS

Filed May 1, 1931

Inventor:

John Young
Festus Young & Co.
Attn.

UNITED STATES PATENT OFFICE

JOHN YOUNG, OF WELLAND, ONTARIO, CANADA

ABC FURNACE CONTROL APPARATUS

Application filed May 1, 1931. Serial No. 534,915.

My invention relates to improvements in electric arc furnace control apparatus and the object of the invention is to provide means for regulating the arc voltage in conjunction with a current regulator so that each electrode will deliver an equal amount of energy in watts into the furnace and the tendency of an electrode to dip and remain in contact with the charge in the furnace will be obviated.

In the usual operation of arc furnaces, particularly those operating on a three phase system, difficulty is encountered in regulating the electric power so that each electrode will deliver an equal amount of energy in watts, and the one or other of the electrodes has a tendency to dip and remain in contact with the metal, so contaminating the charge and making it difficult to control the carbon content. The employment of my voltage regulator cures the above difficulties.

A preferred embodiment of my invention is hereinafter described and illustrated in the accompanying drawing in which:

Fig. 1 is a diagrammatic view of a three-phase arc furnace showing my control apparatus applied thereto, and

Fig. 2 is an enlarged vertical section through my control apparatus.

Like characters of reference indicate corresponding parts in the different views.

1 is the bath or hearth, and 2 are the electrodes. 3 are the furnace bus bars connected to the respective electrodes 2. Such parts are of standard construction as are the current transformers 4 and the circuits 5 as well as the circuits 6 including the current regulator solenoid coil 7.

My voltage regulator comprises a base 8 upon which are mounted three solenoid coils 9, each provided with a sliding core 10. One terminal wire 11 of each coil 9 is connected through a common lead 12 to the bath or hearth 1, and the other terminal wires 13 of the coils are connected to the respective bus-bars 3. The solenoid coils 9 are preferably arranged in triangular formation and a tripod 14 is adapted to rest on the sliding cores 10. The tripod 14 is swingably mounted for tilting movement upon a central standard 15,

as for instance, on a ball and socket fulcrum 16, the ball being provided with a resilient connection between it and the base 8.

Lead wires 17 and 18 from the respective transformer circuits 5 are connected respectively to an insulated contact 19 on the extremity of each leg of the tripod 14, and to an adjustable resilient contact 20 positioned above each contact 19, said contacts 20 being in engagement with the contacts 19 when the tripod is disposed horizontally.

Further standard apparatus is employed which consists of a motor driven winch 21 for raising and lowering each electrode individually, current regulators 22 operating through variations of current in the bus bars 3 through the current transformers 4, magnetic switches 23 and 24 which actuate to throw into circuit the motor driven winch 21 and rotate it in the required direction either to move the electrodes upwardly or downwardly depending upon the fluctuations in current in the bus bars 3, and rheostats 25 in shunt with the current regulator coils 7 for permitting the varying of the current input into each electrode.

Owing to the complexity of the diagram, in the drawing a winch 21 is only shown as connected to the third electrode 2 as well as current regulator 22 connected therewith and with the third rheostat 7. Such apparatus would of course be duplicated with respect to the first and second electrodes 2 and with the first and second rheostats 7.

With the exception of my voltage regulator and its connections all the apparatus described above is now in use and it is only the application of my voltage regulator to such standard apparatus which constitutes my invention.

In operation, each of the three solenoids 9 is energized by a shunt current passing through it from a corresponding bus bar 3 to the furnace hearth. The amount of current passing through these solenoids will vary in accordance with the potential difference between the bus bar and the furnace hearth. When the voltage is the same in all electrodes the tripod 14 will be in a horizontal position, but should there be any

variation in the voltages, the tripod through the action of the solenoids 9 will tilt away from that solenoid having the least current passing through it to a degree depending on the unbalanced voltage conditions between the respective bus bars and the furnace hearth. When this movement occurs the contacts 19 and 20 open, inserting a further resistance into the shunt circuit which causes more current to pass through the particular regulator coil 7 and causing the corresponding electrode to be raised, thus raising the voltage.

From the above description it will be apparent that my voltage regulator relies for its operation on unbalanced conditions of arc voltages and the tripod which coacts with the movable cores responds always to the resultant of the three forces acting on the solenoids.

Furthermore, it will be seen that should the voltages in the bus bars be raised or lowered the apparatus will still continue to function and, in this connection, the windings of the coils 9 could be so designed as to operate over a wide range of voltages.

The apparatus can also be used to open the electric circuit of a relay on a magnetic contactor used in the electric winch motors operating the electrodes and so keep the electrodes from being lowered into the furnace charge.

What I claim as my invention is:

1. In a three-phase arc control apparatus, in combination a furnace hearth, three electrodes, bus bars supplying current to the three electrodes, a current regulating circuit including a current regulator associated with each electrode, and a shunt circuit including a rheostat in circuit with each current regulator, a voltage regulator comprising a magnetic coil connected between each bus bar and the furnace hearth, a movable member superimposed above the coils, a plurality of contacts on the member, a plurality of contacts adapted to coact with the contacts on the member, each pair of coacting contacts being connected into a current regulating circuit and when out of contact with each other causing a further resistance to be inserted into the shunt circuit with a consequent increase of current through the corresponding current regulator, and means due to the weakening of the current in a magnetic coil for causing the member to break contact between the contacts connected with the current regulating circuit associated with such coil.

2. In a three-phase arc control apparatus, in combination a furnace hearth, three electrodes, bus bars supplying current to the three electrodes, a current regulating circuit including a current regulator associated with each electrode and a shunt circuit including a rheostat in circuit with each current regu-

lator, a voltage regulator comprising a magnetic coil connected between each bus bar and the furnace hearth, a movable member superimposed above the coils, a plurality of contacts on the member, a plurality of contacts adapted to coact with the contacts on the member, each pair of coacting contacts being connected into a current regulating circuit and when out of contact with each other causing a further resistance to be inserted into the shunt circuit with a consequent increase of current through the corresponding current regulator, a sliding core in each magnetic coil operatively connected to the member and normally retained in such position by the energized coils that each pair of contacts is in engagement, an increase of current through any pair of magnetic coils with a consequent weakening of the current in the remaining coil causing the breaking of the contact between the pair of contacts connected in the current regulating circuit associated with the weakened coil.

3. In a three-phase arc control apparatus, in combination a furnace hearth, three electrodes, bus bars supplying current to the three electrodes, a current regulating circuit including a current regulator associated with each electrode, a voltage regulator comprising a magnetic coil connected between each bus bar and the furnace hearth, a tiltable tripod member superimposed above the coils, a sliding core in each magnetic coil, each operatively connected to a leg of the member, a contact on each leg of the member, and a contact normally adapted to contact with each contact on the member, each pair of contacts connected in a current regulating circuit.
